UNITED STATES PATENT OFFICE.

GEORGE R. TUTTLE, OF GRASS VALLEY, CALIFORNIA.

ORE-MILLING APPARATUS.

SPECIFICATION forming part of Letters Patent No. 731,634, dated June 23, 1903.

Application filed December 26, 1902. Serial No. 136,549. (No model.)

To all whom it may concern:

Be it known that I, GEORGE R. TUTTLE, a citizen of the United States, residing at Grass Valley, county of Nevada, State of California, have invented certain new and useful Improvements in Ore-Milling Apparatus; and I do hereby declare the following to be a full, clear, and exact description of the same.

The present invention is designed for use in connection with ore stamp-batteries, the object of the invention being the providing of means whereby the necessity of stopping the working of the stamp mill or battery during the operation of dressing the amalgam plates is obviated, thereby permitting the work of the stamp or battery to continue without interruption.

To comprehend the invention, reference should be had to the accompanying sheet of drawings, wherein—

Figure 1 is a perspective view of the apparatus, and Fig. 2 a top plan view of the mechanism disclosed by Fig. 1 of the drawings.

In the drawings the numeral 1 is used to indicate the mortar of an ordinary ore stamp-mill, from which mortar extends a projecting lip 2. To the mill-floor 3 the rails 4 are secured, which rails run transversely to the stamp-mill mortar. Upon the tracks work the rolls or wheels 5 of the tables 6 7, which tables support the amalgamating-plates 8 9.

When amalgamating-plate 8, resting on table 6, is being used, the same stands at right angles to the front of the mortar 1 of the stamp-mill, so as to receive the pulp discharged therefrom over lip 2. The upper end of table 6 and plate 8 rest below the projecting mortar-lip 2, so that the discharge from the lip or the material delivered therefrom falls onto the head-end portion of the amalgamating-plate placed thereunder. The bed of each table inclines toward the lower or discharge end 10, so that the receiving-plate stands at a downward inclination in order that the material discharged thereon will work toward the lower end or distribute itself uniformly over the surface of the plate.

When it is desired to remove amalgamating-plate 8 from the field of operation in order to dress same, table 7, with its amalgamating-plate 9 thereon, is moved toward table 6 until it bears thereagainst. The operator or millman by forcing table 7 transversely

toward the mortar 1 gradually moves table 6 with its plate to be dressed laterally or away to one side of the said mortar until plate 9 assumes the position previously occupied by plate 8. Amalgamating-plate 8 is thus moved to one side and a fresh plate substituted therefor without requiring the stamps to be thrown out of operation.

After the loaded plate has been moved to one side the same is dressed and placed in condition to take the place of plate 9 when required to be dressed. In removing the plate 9 from the field of operation the operation previously described is reversed—that is, table 6, with its dressed amalgamating-plate, is gradually moved into the field of action, so as to force table 7 with its plate to one side of the mortar.

Ordinarily one hour is required, twice a day, to properly dress a set of plates. Without provision being made to substitute one plate for the other without stoppage of the stamp-battery considerable time is lost in "hanging up the stamps" during the change of plates. It is this waste time that the present invention seeks to provide against.

Having thus described the invention, what is claimed as new, and desired to be protected by Letters Patent, is—

1. An ore-milling apparatus comprising in combination with a stamp-mill, a series of tracks arranged transversely to the stamp-mill, a pair of independently-movable tables working thereon, and an amalgamating-plate carried by each table, said plates being alternately moved in front of the stamp-mill to receive the pulp therefrom.

2. An ore-milling apparatus comprising a stamp-mortar, a discharge-lip projecting therefrom, of parallel tracks arranged transversely to the mortar, independently-movable tables working thereon, amalgamating-plates carried by the table, the tables being so arranged that the movement of one table into the field of action forces the other table with its amalgamating-plate therefrom.

In witness whereof I have hereunto set my hand.

GEORGE R. TUTTLE.
